POSTMAN'S UMBRELLA ATTACHMENT

Wayne H. Major, Fort Wayne, Ind.

Application June 16, 1942, Serial No. 447,289

1 Claim. (Cl. 224—5.1)

This invention relates to article supports and has special reference to a support for umbrellas carried by postmen and other persons making house to house deliveries of articles from bags suspended from the shoulder of the carrier.

One important object of the invention is to provide a novel umbrella support detachably attachable to a mail bag or the like and arranged to support an umbrella in such manner as to leave both of one's hands free to handle matter from the bag.

A second important object of the invention is to provide, in such a device, novel means whereby the height at which the umbrella extends above the bag may be regulated.

A third important object of the invention is to provide a novel arrangement of umbrella carrier wherein wind action tending to lift the umbrella when open is resiliently checked.

A fourth important object of the invention is to provide a novel clamping arrangement for an umbrella carrier so constructed that the carrier is supported not only by the mail bag but also by the shoulder strap carrying such mail bag.

With an ordinary umbrella strapped to a person or an article carried by such person so that it cannot freely rotate the motion of the person's body tends to set up a constant oscillatory movement of the umbrella canopy or cover and this is apt to quickly distort and cause breakage of the umbrella frame. Also such a non-rotatable arrangement prevents the umbrella from yielding to blows such as may be produced by the carrier walking too close to a tree or other immovable object.

A fifth important object of the invention is to so mount an umbrella for the purpose set forth that it will be freely rotatable and thus permitted to yield to the movements of a person in walking and also to yield when struck against an immovable object.

With the above and other objects in view, as presently will be apparent, the invention consists in general of certain novel details of construction and combinations of parts hereinafter fully described, illustrated in the accompanying drawings and particularly pointed out in the appended claim.

In the accompanying drawings like characters of reference indicate like parts in the several views, and:

Figure 1 is a front view of the invention showing an umbrella and portions of the bag and strap supporting the same.

Figure 2 is a side elevation of the invention on

a larger scale than Figure 1, the view illustrating the right side.

Figure 3 is a section on the line 2—3 of Figure 1 but on the same scale as Figure 2.

Figure 4 is a fragmentary elevation of the left side of the bag clamp used herein.

Figure 5 is a fragmentary section on the line 5—5 of Figure 1.

Figure 6 is a section on the line 6—6 of Figure 4.

Figure 7 is a section on the line 7—7 of Figure 4.

Figure 8 is an enlarged view of the strap clamp used herein.

As herein shown the bag clamp forming the lower part of this invention is provided with two jaws, A and B. The jaw A lies on the outside of the bag next the body of the user and includes a lower or main portion 10 formed of wood or other suitable material and preferably rectangular in cross-section, the edges being rounded off. This body 10 thus has a flat side 11 which rests against the wearer and the lower end of this side curves outwardly as at 12 to meet the lower flat side portion 13 which engages the outer face of the mail bag M below the hem or lip H. The rounded end 12 eases the fit of the clamp against the wearer and prevents the jaw A from causing pressure against the wearer's lower ribs. Above the flat side 13 the body 10 has a flat side 14 which engages against the hem H and the side 14 is offset inwardly from the side 13 so as to provide an upwardly facing shoulder 15. This shoulder engages beneath the bottom edge of the hem and aids in preventing the clamp from slipping upwardly and becoming disengaged from the bag. Teeth or other gripping devices (not shown) may be applied to the inner side of the jaw B that engages the inside of the mail satchel to firmly hold the bag against the lower portion 13 of the jaw A. If desired the gripping faces of both jaws A and B may be roughened like a file, teeth punched through like a grater or any other suitable gripping means may be employed to securely hold the bag between the gripping jaws. The top of the body 10 is flat and from this flat top a bore 16 extends downwardly to terminate quite close to the lower end of the body. The bore 16 is of slightly greater diameter than the umbrella shaft S, the difference in diameters being very small so that the shaft fits the bore 16 with a sliding fit.

On the upper end of the body is fixed a tubular housing 17 having a centrally perforated closure 18 at its upper end. This closure is fixed with relation to the housing and this may be done in a variety of ways. For instance, the closure may

be integral with the side wall of the housing, it may be welded or brazed in place or it may be held by a flange or by tabs turned inwardly over its upper face. The manner of holding the closure forms no part of the present invention and accordingly the several manners of securing the same have not been illustrated. The opening in the closure 18 is co-axial with the bore 16 and the diameter of the opening is substantially equal to the diameter of said bore. Within the housing 17 is a perforated plate or washer 19 of similar dimensions to the closure 18. Also in the housing 17 is a sleeve 20 having an annular flange 21 extending therearound intermediate the ends of said sleeve. The sleeve is of such internal diameter as to receive the shaft S and a set-screw 22 is screwed through the sleeve wall to engage said shaft and secure the latter in adjusted position in the sleeve. In order to afford access to the set-screw 22, the housing 17 is provided with a window or access opening 23 as best seen in Figure 4. The sleeve 20 is normally held in the bottom of the housing by a coiled compression spring 24 which, at its lower end, surrounds the upper end of the sleeve and engages on the flange 21. This spring 24 may be larger in diameter at its upper end, in order not to interfere with the shaft S as it enters the bore 16. The upper end of the set collar 20 may be beveled on the inside to provide a guide for the shaft S as it is inserted in the bore 16. The upper end of this spring engages against the under face of the closure 18 around the opening in said closure. Projecting forwardly from the housing 17 is a pair of spaced hinge ears 25.

The jaw B, which fits inside of the bag in use, consists of a channel shaped lower part 26 and a tubular upper part 27, the latter forming a handle or grip. The channel is positioned with its web 28 confronting the side portions 13 and 14 of the jaw A and from this channel extend a pair of hinge ears 29 which fit between the ears 25. A pivot pin 30 extends through these ears and is suitably secured as by riveting the ends. A coiled torsion spring 31 surrounds the pin 30 between the ears 29 and one end of this spring extends into the tubular portion 27 and presses against the front wall thereof. The other end of the spring 31 extends upwardly to engage between lugs 32 formed on the housing 17. This spring constantly urges the lower ends of the jaws A and B toward each other.

On the housing 17 is an eye 33 to which is connected one end of a chain or other flexible strand 34. A shaft clip 35 is attached to the other end of this chain. The clip 35 is preferably formed from a single length of wire of sufficient temper to provide the necessary springiness. This wire is bent adjacent one end to provide a terminal portion 36 and a substantially parallel portion 37 forming a lower strap engaging jaw. From the portion 37 the wire extends upwardly as

at 38 and is bent to provide parallel portions 39 and 40 forming the upper strap engaging jaw and from the portion 40 the wire extends forwardly at 41 and then backwardly as at 42 to form a chain engaging loop. Finally the remainder of the wire is bent laterally and forwardly as at 43, the portions 42 and 43 forming an umbrella shaft grip as shown in Figure 5, the strap being shown at S'.

10 In use the upper or handle parts of the two jaws A and B are grasped and pressed toward each other to open the bag clamp. The lower end of the jaw B is inserted in the bag close to the bag side and pressure on the upper jaw parts is 15 relaxed. This permits the bag to be firmly grasped. The strap clip is now forced onto the bag strap and the shaft of the umbrella swung to be gripped thereby. When in this position the umbrella shaft will be held close to the user's 20 body without the assistance of either hand. If a gust of wind catches beneath the umbrella and tends to lift it the spring will absorb the shock and the umbrella and clamp will not tear loose from the bag.

25 If it is found that the umbrella canopy is not at the proper height the device may be removed from the bag and the shaft turned until the set-screw is opposite the window whereupon a screwdriver is used to loosen the screw, the shaft moved up or down to suit the user and the screw again tightened.

30 The bore 16 is preferably slanted in such a manner as to incline the umbrella shaft rearwardly at its upper part so that it will lie close to the user's body. It is also to be noted that the spring 24 is so shaped and mounted that it is held concentrically of the bore and thus will not interfere with the insertion of the umbrella shaft.

35 What is claimed as new is:

40 In a postman's umbrella carrier of the character described, a body having a bore extending downwardly from its upper end, a tubular housing telescopically and non-rotatably mounted on the upper end of the body, said housing having an upper end closure provided with an opening substantially equal in size to and aligned with said bore, an umbrella shaft projecting downward through said opening and bore, a collar within said housing surrounding the shaft above said body, a set-screw securing the collar releasably in selected position on the shaft, said housing having a lateral opening affording access to said set-screw, a flange extending circumferentially around the collar intermediate the ends of the 45 collar, said set-screw being located below the flange, a coiled compression spring surrounding said shaft with one end bearing against the housing closure and its other end resting on said flange, and the end of the collar above the flange 50 engaging in and centering the spring around the shaft.
